UNITED STATES PATENT OFFICE.

CHARLES L'ENFANT, OF NEW YORK, N. Y.

BILL FOLD.

Application filed March 31, 1926. Serial No. 98,651.

This relation relates to bill folds and an improved method of making the same, and has for its primary object to provide a new method of assembling and connecting the 5 parts of the bill fold whereby such operations may be expeditiously performed, and the neat appearance of the bill fold, even after long use thereof, will be preserved.

In leather bill folds as heretofore manufactured, the outer and inner walls thereof between which the bills are to be placed are connected at their opposite ends and along their lower longitudinal edges by lines of stitching. Obviously, the line of stitching 10 between the lower edge portions of the walls forming the pocket of the bill fold limits the depth of said pocket. Thus, when a large number of bills are carried in the bill fold, the inner and outer walls are expanded 15 or separated by the bills only between the open side of the pocket and the longitudinal line of stitching connecting said walls. The lower edges of these walls beyond said line of stitching will therefore bend or flex 20 into numerous folds relative to the main portions of said walls between which the bills are contained so that the closed longitudinal edge of the bill fold rapidly acquires 25 a distorted, ragged appearance.

My improved method overcomes the objection above referred to and provides a 30 pocket in the bill fold having a depth extending to the extreme lower closed edge of the bill fold so that the inner and outer walls 35 will be uniformly expanded across their entire width when the bills are inserted in said pocket. In other words, the depth of the pocket is not limited by the line of stitching connecting the inner and outer 40 walls so that when said walls are doubled or folded, the fold lines or creases thereby formed will be uninterrupted or unbroken across the entire width of the bill fold.

It is also a further general object of the 45 invention to provide a leather bill fold having certain novel structural features whereby the manufacturing cost may be appreciably reduced and the durability and general utility of the article increased.

With the above and other objects in view, 50 the invention consists in the improved bill fold, and in the method of making the same as will be hereinafter more fully described, 55 illustrated in the accompanying drawings, and subsequently incorporated in the subjoined claims.

In the drawings, wherein I have disclosed one simple and practical embodiment of my present improvements, and in which similar reference characters designate corresponding parts throughout the several views,—

Figure 1 is an inner side elevation of the bill fold embodying my improvements showing the same open;

Fig. 2 is a fragmentary elevation showing the first step in assembling the inner and outer walls of the bill fold;

Fig. 3 is a sectional view taken on the line 3—3 of Fig. 2;

Fig. 4 is a view similar to Fig. 2, showing an intermediate step of the method after the two walls have been connected;

Fig. 5 is a sectional view taken on the line 5—5 of Fig. 4.

Fig. 6 is a fragmentary inner side elevation showing the next succeeding step of the method to that illustrated in Fig. 4;

Fig. 7 is a sectional view taken on the line 7—7 of Fig. 6;

Fig. 8 is a detail section taken on the line 8—8 of Fig. 6;

Fig. 9 is a fragmentary inner side elevation of the completed bill fold, and

Fig. 10 is a detail section taken on the line 10—10 of Fig. 9.

Referring in detail to the drawings, in carrying out my new method, I first provide an outer wall 5 of leather or other flexible material and an inner wall 6, also of leather or other desired flexible material. The outer wall 5 is of greater length and width than the inner wall 6, and, upon the inner or unfinished side of said outer wall, a fabric lining sheet 7 is arranged, one longitudinal edge 8 of the wall 5 being inwardly turned and stitched to the edge of said lining sheet as indicated at 9. This lining sheet is of less length and width than the wall 5, said wall at its ends projecting beyond the ends of the lining sheet in the manner shown in Fig. 2 of the drawings. The other longitudinal edge of the lining sheet is adapted to be secured to the face of the wall 5 by means of a suitable glue or adhesive. It will be noted from reference to Fig. 3 of the drawings, that the extreme edge of the inturned portion 8 of the wall 5 is folded on itself and that the edge of the lining sheet 7 is stitched to this fold so that the stitching line will be practically concealed.

Upon the inner or unfinished face of the

inner wall 6 of the bill fold a plurality of layers of fabric 10 are arranged and constitute a reinforcing lining for said inner wall. The outer layer of the fabric 10 has 5 its free longitudinal edge stitched to the inwardly turned edge 11 of the wall 6 as shown at 12. The lining fabric 10 extends the full length of the wall 6 and adjacent to the ends thereof is also secured to said 10 wall by the stitching 13.

The inner and outer leather walls 5 and 6 thus provided with the fabric linings are now arranged upon each other with their right sides opposed and in contact, as shown 15 in Fig. 3 of the drawings, the longitudinal edges of said walls opposite the inturned edges 8 and 11 respectively, thereof, being in registering relation with each other. The two walls are then connected in spaced relation to the latter edges thereof by the longitudinal line of stitching 14 which also extends through the layers of fabric 10 on the inner wall 6. In the drawings, it will of course, be understood that for reasons of 25 clarity, I have shown the thickness of the several layers of material greatly exaggerated.

In the next step of the method, the two walls 5 and 6 are reversed in relation to 30 each other, or in other words, the outer wall 5 is folded around the connected longitudinal edge of the inner wall 6 in the manner indicated in Figs. 5 and 7 of the drawings, said outer wall being of sufficiently greater 35 width than the inner wall to provide a freely flexing edge portion 15 between said outer side wall and the folded edge 16 which is secured to the inner face of the inner wall 6 by the stitching 14 and still position the 40 inturned edge 8 of the outer wall 6 beyond the inturned edge 11 of the inner wall at the open side of the bill fold.

After thus providing the seam 14 between the two parts or walls of the bill fold, the 45 projecting ends of the outer wall 5 are then turned inwardly and downwardly over and upon the ends of the inner wall 6 as shown at 17, the extreme edges of these inturned ends of the wall 5 overlying the lines of stitching 13 connecting the ends of the inner wall 6 with its lining 10. Preferably, 50 I use a suitable adhesive for permanently securing the inwardly turned ends of the outer wall to said inner wall 6. With a 55 suitable tool, pressure is then applied along the line of stitching 14 to form shallow channels indicated at 18 in the face of the wall 6, and to also compress the stitching so that it becomes practically invisible.

60 It will be seen that in the above manner, I provide a bill fold wherein the connecting seam 14 does not limit the depth of the bill receiving pocket, but the bills may be inserted in said pocket with their lower edges 65 in contact with the flexible edge 15 of said

outer wall 5. It is, therefore, evident that when a large number of bills are placed in said pocket, the inner and outer bills may expand or yield uniformly across their entire width and there will be no portion projecting 70 beyond the connecting seam at the closed edge of the pocket which is unexpanded. Therefore, when the two walls of the bill fold with the enclosed bills are folded on each other one or more times, such folds will 75 form creases extending in unbroken lines entirely across the full width of the walls 5 and 6. By thus eliminating the relatively thin projecting edge at the closed side of the pocket, the said edge of the bill fold will not 80 become wrinkled or distorted and the neat appearance of the bill fold even after long continued use, is thus preserved.

From the foregoing description considered in connection with the accompanying drawings, the construction of my improved bill fold, as well as the several steps involved in the method of producing the same will be readily understood. It will of course, be apparent that my improved method may be advantageously employed in the production of bill folds of various sizes and of either the double or triple fold type. While I have illustrated a particular arrangement of the reinforcing lining 10 for the inner wall of the bill fold, it will be apparent that this is not an essential feature and that, if desired, this lining may consist merely of a single thickness of material, similar to the lining 7 90 for the outer wall 5. The device may also be susceptible of various other modifications in the form, proportion and arrangement of its several parts while retaining the essential characteristics of the novel features herein disclosed, and I therefore, reserve the privilege of resorting to all such legitimate changes therein as may be fairly embodied within the spirit and scope of the invention 95 as claimed.

I claim:

1. A bill fold comprising inner and outer flexible walls, said outer wall having one of its longitudinal edge portions turned around and inwardly over the corresponding edge portion of the inner wall and permanently secured to the latter at a point in spaced relation to the extreme longitudinal edge thereof to thereby provide a freely flexing edge portion of said outer wall enclosing the edge portion of the inner wall and constituting a closure for the lower edge of the bill fold pocket whereby the depth of said pocket is equivalent to the full width of said inner wall, and means connecting the corresponding ends of said walls with each other to close the ends of the pocket.

2. A bill fold comprising inner and outer flexible walls each having a fabric lining sheet upon its inner side, said outer wall having one longitudinal edge thereof turned

inwardly around the corresponding longitudinal edge of the inner wall and connected with said wall in spaced relation to the extreme longitudinal edge thereof by a line 5 of stitching extending through said inner wall and the turned over edge of the outer wall and also securing the lining upon the inner wall to thereby provide a freely flexing edge portion of said outer wall enclosing the 10 corresponding edge of the inner wall and forming the closed lower edge of the bill

receiving pocket having a depth substantially equivalent to the width of said inner wall, and the opposite end edges of said outer wall being inwardly turned over the corresponding end edges of the inner wall and 15 permanently secured thereto to close the opposite ends of the bill fold pocket.

In testimony that I claim the foregoing as my invention, I have signed my name 20 hereto.

CHARLES L'ENFANT.
